UNITED STATES PATENT OFFICE.

WILLIAM E. WILSON, OF MASON CITY, IOWA.

REISSUED

FIREPROOF BUILDING-WALL.

1,171,913.

Specification of Letters Patent. Patented Feb. 15, 1916.

Application filed May 12, 1914. Serial No. 838,061.

To all whom it may concern:

Be it known that I, WILLIAM E. WILSON, a citizen of the United States, resident of Mason City, county of Cerro Gordo, and 5 State of Iowa, have invented certain new and useful Improvements in Fireproof Building-Walls, of which the following is a specification.

My invention relates to a fire-proof building wall, and the object of the invention is to hermetically seal both the horizontal and vertical joint between the blocks comprising the wall, to the end that the passage of heated or cold air through the joints in the 15 wall will be prevented.

A further object is to provide a wall construction which will be simple and economical and at the same time thoroughly insulate the building against frost and heat.

20 A further object is to provide a wall construction adapted for use in building silos.

The invention consists generally in various constructions and combinations, all as hereinafter described and particularly 25 pointed out in the claims.

In the accompanying drawings forming part of this specification, Figure 1 is a perspective view of a wall with my invention applied thereto, Fig. 2 is a perspective 30 view, showing the longitudinal and vertical insulating pads in their assembled position, Fig. 3 is a perspective view of the form of vertical pad shown in Fig. 2, Fig. 4 is a perspective view, showing a longitudinal 35 pad adapted to fit within the central opening in the block and extending through the vertical pad between the blocks, Fig. 5 is a perspective view of the form of vertical pad used with the arrangement of Fig. 4, Fig. 40 6 is a perspective view of the form of vertical pad used in Fig. 1.

In the drawing, 2 represents the blocks of which the wall is composed. As shown, these blocks are provided with a series of 45 longitudinal openings 3 on each side of the vertical middle portion of the block, forming; when the blocks are placed in courses in the wall, a series of passages running horizontally through the wall and having 50 the function, as usual in blocks of this kind, of preventing the passage of moisture from one surface of the wall to the other. I have shown three of these passages on each side of the block, but a greater number may be 55 employed according to the preferred size and shape of the block. 4 is a central pas-

sage running through the block from end to end, and above and below these passages are longitudinal recesses 5 separated from the central passage by walls 6. These recesses 60 are of suitable depth and preferably corresponding in width to the central opening 4, and when the blocks are laid in courses the recesses in the blocks of the same course will be in alinement with one another and 65 form continuous passages in the joints of the blocks, from one end of the wall to the other. In these passages I place horizontal insulating strips or pads 7 of suitable width to lap the horizontal joints between blocks 70 of adjacent courses so that the upper portion of a pad will be in the recess in the bottom of one course, while the lower portion of the same pad will lie in the upper part of the blocks in the course next beneath, 75 thereby bridging the horizontal joint between the courses and positively preventing the passage of heat and cold through this joint. In connection with this horizontal pad I prefer to use a vertical pad 8 of 80 greater width than the central opening, and closing the ends thereof at each end of a block, and of less width than the thickness of a block and of sufficient length to cover the central opening from the top to the 85 bottom thereof, thereby sealing this passage and forming a dead air chamber in each block. This pad is also made of insulating material, and positively prevents the passage of heat or cold through the joint. To 90 combine this vertical pad with the horizontal one I prefer to provide transverse slits 9 arranged at intervals in the upper and lower edges of the horizontal pad and in staggered relation to one another, and extending partially therethrough, and of sufficient width to receive the ends of the vertical pad and coöperate therewith to positively close the horizontal and vertical joints and thoroughly insulate one side of 100 the wall from the other.

Instead of cutting notches or slits in the longitudinal pads I may provide notches 10 in the ends of the vertical pad 8 of sufficient depth to receive the edges of the adjacent longitudinal pads to interlock therewith, the result being the same as slitting the longitudinal pads and inserting the vertical pads in these slits.

I may also provide insulating pads 11, 110 shown in Fig. 4, adapted to fit within the central openings 4 in the blocks and extend

through these openings from end to end of the blocks and abut at each end against the vertical pads, or slots 12 may be provided in these vertical pads and the pads 11 be 5 in the form of continuous ones running through the blocks of each course and fitting within the slots in the vertical pads. With this arrangement of the horizontal pads above and below the blocks and extending 10 through the central openings therein, the insulation will be substantially continuous from the top to the bottom of the wall, there being only a comparatively shallow wall or partition separating the central 15 opening from the horizontal pads immediately above and below it.

The wall is adapted not only for dwelling house construction, but is also used in silo construction, where a complete insulation 20 against the passage of heat or cold through the wall is desirable.

I claim as my invention:

1. A wall composed of a series of blocks, each having a central opening extending 25 through the block from end to end thereof, and each having a longitudinal, independent opening extending from end to end of the block, on each side of said central opening, each block having longitudinal, centrally 30 arranged recesses above and below its central opening, vertical insulating pads inserted between the abutting ends of the blocks in the same course, horizontal pads fitting within the recesses in said blocks and 35 interlocking with the ends of said vertical pads at their point of intersection, said vertical and horizontal pads closing the vertical and horizontal joints in said wall.

2. A wall composed of a series of blocks, 40 each having a central opening extending through the block from end to end thereof and each having a longitudinal, independent opening extending from end to end of the

block on each side of said central opening, each block having longitudinal, centrally 45 arranged recesses above and below its central opening, insulating pads inserted between the abutting ends of the blocks in the same course, horizontal pads fitting within said central openings and extending lengthwise 50 thereof, similar pads fitting within the recesses in said blocks and interlocking with the ends of said vertical pads at their points of intersection, said vertical and horizontal pads closing the vertical and horizontal 55 joints in said wall and insulating said walls and joints against the passage of heat and cold.

3. A wall composed of a series of block, each having a central opening extending 60 through the block from end to end thereof and each having a longitudinal, independent opening extending from end to end of the block on each side of said central opening, each block having longitudinal, centrally 65 arranged recesses above and below its central opening, vertical insulating pads inserted between the abutting ends of the blocks in the same course and having centrally arranged slots to register with the 70 ends of said central openings, horizontal pads fitting within the recesses in said blocks and interlocking with the ends of said vertical pads at their points of intersection and similar horizontal pads passing through said 75 central openings and through the central slots in said vertical pads, said longitudinal and vertical pads insulating said walls and joints against the passage of heat and cold.

In witness whereof, I have hereunto set 80 my hand this 28th day of April, 1914.

WILLIAM E. WILSON.
